AUTOMATIC GUN

Robert F. Hudson, Richmond, Va.

Application June 26, 1929, Serial No. 373,719½

33 Claims. (CL. 89—2)

The present gun is a gas set, mechanically operated, automatic gun, the power for operation being obtained by passing a portion of the powder gases into a gas cylinder for the purpose of compressing a main spring in a forward direction, the energy stored in the main spring being used to serve the purposes of unlocking, driving the bolt and attached parts of the mechanism to the rear, and for compressing the bolt spring. 5 This gun, similar to any automatic gun, must be retracted by hand in order to load the first cartridge into the chamber. After the first cartridge has been loaded, the trigger released, and the cartridge fired, the automatic action starts. 10 The bolt spring, which has been compressed during the rearward movement, returns the bolt and attached mechanism forwardly, provided the trigger is pulled to prevent the retracting catches from holding the mechanism to the rear. During 15 the rearward movement the cartridge guide and ejectors are held in the housing by the bolt until the bolt clears them and allows the ejectors to be forced out of their housings by the ejector springs, so that the ejectors strike the fired cartridge case above the center line, which causes 20 the fired case to be driven from the face of the bolt and out of the receiver. 25

When the cartridge is fired, a portion of the powder gases are permitted to enter the gas cylinder and drive the piston forwardly, which compresses the main spring, the surplus energy from the powder gases in the gas cylinder being transmitted to the buffer by a positive link which connects the gas piston and the buffering 30 element at the forward end of the main spring housing. The gas used from the barrel is tapped at a point of maximum pressure, maximum temperature, and where the velocity is still increasing. 35

It will be found from the art of using gas power for operation, either direct or indirect, that two basic and distinctly different methods of operating are available. First, if advantage is taken of the maximum energy available from 40 a portion of the powder gases, it must be taken at a point where the ordinate of the powder curve is a maximum, and it must be used with a powder that will retain this maximum value of the ordinate through a considerable portion of the 45 curve. This means that a progressive burning powder is necessary to obtain the maximum advantage to be gained when the gases are to be used at a point of maximum pressure, maximum temperature and one at which the velocity is still 50 increasing. 55

The other distinct method of using powder gases for operation of the mechanism, or for counteracting the base pressure, or recoil, must use the only remaining source, i. e., the velocity of the powder gases must be taken advantage of, 5 which naturally indicates that this can only be accomplished at or near the muzzle of the gun. At this point, the ordinate of the powder curve is a minimum, which shows that the energy available is spent at the sacrifice of an increase 10 in velocity. This being the case, apparently advantage must be taken of the maximum velocity to further counteract the base pressure or recoil. This may be accomplished by providing a so-called muzzle brake, which may consist of baffles, deflection plates, or slots, or any other means of checking the velocity of the powder gases to utilize the energy available from the gas, at or near a point of maximum velocity. The powder curve ordinate being a minimum, 15 shows that the energy available, due to temperature and pressure, cannot be used at this point. The total energy available from the powder gases, their period of application, the time of the application of base pressure, or recoil, has been 20 thoroughly analyzed. 25

The present automatic gun has been designed to specifically utilize the total energy available, by coordinating the time of application as near as physically possible to coincide with the period 30 of application of the base pressure, and advantage is taken of the position of the maximum ordinate of the powder curve by taking off the operating power immediately after the maximum ordinate has been reached. This also gives the 35 maximum period of application of the greatest energy available over as long a distance of bullet travel in bore as is possible. The application of the maximum energy available is dissipated in terms of stored operating energy, the excess is 40 absorbed in a forward direction by a buffer means. The bullet is still in the barrel during this period of application, due to the application of the energy to the gas piston immediately after the maximum ordinate of the powder curve 45 has been reached. The maximum ordinate, or a mean maximum ordinate, is sustained with a progressive burning powder for more than one-third the distance traveled by the bullet in the barrel, and, therefore, the energy storing means 50 has coated and relayed its energy to the buffering element during this time. The bullet leaves the barrel along with the powder gases at the maximum velocity obtained in the barrel, with the pressure minimum. The muzzle brake or velocity 55

dissipater, whether it be a reflection mechanism or retracting mechanism does not matter so long as advantage is taken of maximum velocity of the gas which emerged from the muzzle unit at a greatly reduced velocity, can serve only to reduce recoil, due to the arresting of the forward velocity of the powder gases.

What would appear to be a fine distinction between the present automatic gun and other 10 automatic guns, using a portion of the powder gases for operating directly or indirectly, is, in reality, a very distinct difference, and has the same parallel as two moving objects racing each other in opposite directions.

15 The gas piston of the present type of automatic gun travels a distance greater than the length of the cartridge in a forward direction with no mechanical connection, or any other type of communication between the gas piston and the bolt 20 mechanism. In fact, during this forward movement of the gas piston, and the bullet travel in the barrel, no part of the mechanism of this gun moves to the rear, and the only reaction in the rearward direction is the base pressure on the 25 cartridge case itself. The object of the gases and piston moving forwardly from first thought, will not be apparent to either the layman, engineer, or gun expert. The first advantage of prime importance is the delayed action, i. e., allowing the 30 bolt and breech lock to remain locked against the fired cartridge, with no linkage whatsoever to start the unlocking until a considerable period has elapsed after the bullet has left the gun. This insures the dissipation of the entire base 35 pressure in the fired cartridge case so that no strain is placed on either mechanism or cartridge case when extraction is performed. This also assures a positive sealing of the chamber which reduces erosion of the bullet seat, and the mechanism of the bolt; the primer is firmly supported until all pressure has left the cartridge case; and no leakage around the primers can occur, a most serious defect found with other automatic guns 40 in general. The main disadvantage with leaky 45 primers is the highly erosive effect of the primer gases on the face of the bolt which destroys the usefulness of the bolt, the most expensive component of automatic guns. Leaky and blown primers are a source of endless trouble with automatic guns. In automatic guns in general, this 50 condition is greatly aggravated by attempting to extract the fired cartridge case before the pressure in the case has been eliminated or dissipated.

Again, it might be apparent, on first thought, 55 that the selection of the port for tapping the gases from the barrel should be at a point of maximum pressure and maximum temperature. The art does not show this, and until a very recent date the art could not have shown this, 60 as no progressive burning powders were available, and were not available during the period of development of a single automatic weapon, regardless of caliber, in use at the present time by any country in the world. It was only natural, in the 65 analysis of present-day requirements for an automatic gun that this most important factor should have received serious consideration. It is well known in the art that the powder curve for quick burning powder, which was the only powder in 70 universal use until a very recent date, has a maximum ordinate, a very short distance from the breech of the barrel, and which diminishes most abruptly and is practically spent as to pressure and ordinate value before one-fourth the length 75 of the barrel has been reached.

It is only natural that previous consideration was not given to the use of this peak as it was of such short duration that it only represented a blow similar to the present existing operating principle of velocity, muzzle sleeve, or muzzle part 5 type of gas automatic gun. This ordinate was not sustained to enable the mechanism to perform work that could be harnessed with positive uniformity. Having discovered the main advantage to be obtained with energy available 10 from the powder curve of a progressive powder, the analysis was continued to determine the energy that should be taken from the energy available from the powder charge, without diminishing the available energy under the powder 15 curve.

The second consideration naturally followed to determine the point at which the gases should be tapped in order to have the gases deliver their energy to the piston and communicate it to the 20 counterrecoil buffering elements. This point having been determined, namely, the point at which the maximum ordinate appears on the powder curve, less the dimension forwarded on the power curve found necessary to handle the heat effect 25 from the powder gases, it still had to be determined what timing was necessary to insure that the counterrecoil element (which is an energy dissipating element acting in a forward direction) was so applied that it would be co-acting 30 with the base pressure (the element which contributes to the recoil of the gun). This was determined and verified and the counterrecoil restraining members were calibrated to withstand twenty-five per cent. less energy than is exerted 35 by the counterrecoil elements. The acid test is: Will the breech lock remain locked after the restraining cap is broken, or will it unlock before the cap is broken? Should the breech remain 40 locked, it would mean that the base pressure (recoil source) would have been exerted, and the free recoil found would be approximately the equation shown below:—

$$VF = \frac{PV + 4700C}{W}$$

C=Weight of powder charge

W=Weight of gun

P=Weight of bullet

V=Velocity of bullet

VF=Velocity of free recoil

From the energy equation $KE = \frac{1}{2}MV^2$ it will be seen that the base pressure contributes to the recoil of the gun in the ratio of the weight of 55 the gun to that of the bullet and to the velocities of the two squared. However, should the recoil restraining calibrated element yield after the bolt is unlocked, it will show that these two forces were co-acting for the reason that the energy 60 used in the counterrecoil element is very similar in comparison to that available in the bore of the gun. Again, the weight of the parts of the counterrecoil element that has moved in a forward direction is roughly 100 times the weight 65 of the bullet, so it can be seen that velocity acquired by these parts is extremely low as compared to that acquired by the bullet; and yet, the velocity of the counterrecoil parts moving in the forward direction will be more than 10 times the 70 velocity acquired by the mass of the gun tending to move in the rearward direction due to the base pressure, as the ratio of weight of the counterrecoil parts moving in a forward direction to the weight of the gun is less than 1 to 40.

It can be readily seen that a tremendous advantage is to be gained as the velocity contributes to the energy of the recoil or counterrecoil as the square of their values, whereas the weight contributed to their recoil or counterrecoil energy is available as their first power. The utilization of the energy from the barrel at the maximum ordinate and highest temperature, as well as maximum pressure, and when the velocity is increasing, makes available a temperature-pressure energy component acting in a forward direction, which is dissipated in the forward direction.

This unit is utilized as part of the counterrecoil element as the velocity is relatively lower. A dissipation of the temperature and pressure results in an energy component in the forward direction which also is co-acting with the base pressure exerted in the opposite direction. The energy used for counterrecoil must be coordinated with the time of application, nature of application, the heat and pressure to be dealt with, and coordination with the utilization of the velocity counterrecoil unit, which is distinct and apart from the pressure-temperature unit, of counterrecoil, but is so closely associated with and co-acting that the total counterrecoil available and base pressure must be considered together when the maximum counterrecoil is to be expected.

From the foregoing, a clear distinction can be seen between this new type of gas energized mechanism, mechanically operated, and the conventional existing strictly gas operated automatic guns. The conventional type not only develops the hammer blow as its operating component, but exerts this hammer blow at the most critical time of operation so as to create the greatest disturbance to offset stability and, in addition, adds to the recoil of any automatic weapon.

It can be readily seen that when a piston is caused to be driven to the rear it must be arrested, whether it be arrested through a toggle link, a buffer, or both. This is bound to be co-acting with a base pressure in the same direction, or otherwise the gun would not operate. To verify this, it is only necessary to fire a very few shots from an automatic rifle which will demonstrate the inability of the marksman to hold the rifle on the target, due to this gas operating element being driven to the rear and returning with the same disturbing effect, as the return occurs after the pressure or recoil has reduced and caused the gun to be displaced below the normal aiming point, whereas a movement to the rear causes a disturbance above the aiming point. Again, one of the most disturbing effects is the fact that automatic fire builds up the recoil and is actually greater after the seventh or eighth shot is fired than when the first shot is fired. This is true for the direct acting gas operating guns due to the fact that all direct acting gas operated guns do not dissipate the recoil between each shot. The blow exerted to operate the gun, therefore, is not dissipated for each shot, as the dissipation can only be acquired with a decided delayed action and with the operation element exerting a forward force and not a backward force.

Another consideration is the offsetting of the disturbing effects of recoiling and counterrecoiling units of the gun. To accomplish this, automatic guns of the past have used steep ramps or cams for braking the energy stored in the parts, which, in some cases, are combined with the lock-

ing element. This phase of automatic guns has been thoroughly analyzed and, in the present gun, steps have been taken to overcome this most serious defect.

The arresting of the recoil and counterrecoil parts with the line of action a considerable distance from the bore of the gun is entirely overcome in the present gun by the provision of a power storing means so that the gun can be operated mechanically, advantage having been taken of the mechanical operation to disconnect the operating power to overcome the hammer blow exerted with recoil barrels, and it is also disconnected after the full stroke is completed. The surplus energy necessary to insure operation under variable friction conditions due to temperature, lack of lubrication, dirty mechanism, defective ammunition, burrs, etc., is not absorbed by a buffering element whose application or action line is a considerable distance from the axis of the bore, but is absorbed by a buffering element directly connected to the barrel, placed in as close proximity as possible. In the first place, this reserve energy is cut to a minimum as it is not necessary to store sufficient energy to return the barrel to battery or to return elements to the forward position that have any appreciable weight in the present gun. This is a most important factor when automatic guns are fired at an elevation. Again, the mechanical operation, as against the action of a blow, insures uniform regulated speed of fire of the gun. The necessity for locking and unlocking the breech lock with a steep angle is eliminated as the locking means is not used in the present gun for braking the recoil or counterrecoil force. Indeed, the reverse is true, as the locking element is not used for arresting the recoil and counterrecoil force. It is actually cushioned to overcome any tendency to lock and unlock with a harsh or blow action. This feature alone, makes it possible to use a very flat angle of locking, an angle slightly above the friction angle, whereas all automatic guns in existence use an abrupt angle of 40° or more, which not only exerts unnecessary strains on the mechanism, but disturbs stability of the mechanism and causes excessive wear and breakage of parts. In the original study and analysis of the specifications of the present automatic gun, an exhaustive investigation was made of the methods of presenting the breech lock to the locking recess in the frame. The best comparison of the trend of thought on this subject can be summarized as follows:—

To provide a lock which will be locked with the least shock and yet be positive. To have the lock travel as near as possible at the same velocity at the time of locking as that of the bolt, and to have the lock take up the velocity of the bolt just before and during unlocking.

Practically all automatic weapons in existence use a breech lock that is entirely stationary, or one that is moving with an extremely low velocity as compared with the velocity of the locking element with which it mates.

In the present gun, the breech lock is carried with the bolt. The parallelism is exactly the same as would be encountered in moving a given weight, a definite height on a high speed train, as compared with the same weight moved the same height by the same person attempting to raise it from a mail-bag arm. Some automatic weapon designers resort to a method of locking by rotating the bolt after it has reached its forward position. While this method has some ad-

vantages over the method of locking a stationary breech lock, it has a disadvantage in that it is necessary to overcome the energy of translation before energy of rotation can be accomplished. To do this, the locking angle must be extremely steep to break the force of the damaging effect that would be encountered in attempting to lock with a flat angle. A second consideration is that the breech lock should be positioned to the forward face of the locking recess and not left to interfere with the rear locking face of the recess. Advantages have been taken of this in the present gun as the momentum acquired by the bolt and breech lock are directly portioned to their weights, and when the bolt is arrested against the cartridge, the breech lock, in attempting to continue its path, gains the forward face of the breech lock guide of the bolt, which is in the position to present the breech lock to the locking recess against its forward face, and not its rear face. To prevent pinching or wedging, and to insure positive locking in case of an oversize cartridge, the rear face of the breech lock and of the breech lock recess are provided with a slight angle to give clearance in locking and to obtain wedge action in the final stage of locking. Furthermore, the advantage to be gained with a flat angle of the locking cam is that the resultant of this locking effort is more nearly parallel with the base pressure and, consequently, is not a disturbing element as to stability. The locking element of the present automatic gun is a most powerful locking means, yet a locking element that requires the least locking effort, thus making it possible, and advantage has been taken of this, to cushion the locking element.

In analyzing the preliminary design of the present automatic gun, serious consideration was given to the effects of the carrying and carried parts. When the gun is fired, the gas piston carrying the cross-head and clutch compresses the main spring and is finally arrested by the counterrecoil buffering element. No part of the receiver mechanism is in motion during this part of the cycle. When the cross-head has reached its forward position, the clutch engages the piston rod. The rear end of the piston rod which is against the frog transmits the energy of the main spring to the frog. When the frog moves to the rear, the bolt and breech lock as a unit are carried to the rear by the frog under the action of the main spring. The frog is the driven member, the main spring is the driver, and the breech lock is cammed down and held in the depressed position, as the retarding effort of the bolt tends to keep the breech lock in its lower position. As the bolt is driven to the rear, the bolt spring is compressed and the bolt and frog are finally arrested by the action of the regulating buffer. The regulating buffer can be throttled to govern the rate of recoil as the main spring exerts a constantly applied force which is distinctly different from the blow received by the bolt element of a directly gas operated gun or a gun operated from a blow transmitted by a recoiling barrel. This provides an extremely simple speed regulating, absorbing element.

In case the trigger is pulled and released, a single shot can be fired either with the mechanism held in the retracting position, or with the mechanism closed on a cartridge, as desired. This feature is very important, as no automatic gun provides both an automatic retracted ar-

rester and a closure on a cartridge without fir-
ing. This feature is also of extreme importance when feeding from a clip or magazine, and yet can be used very efficiently for a belt as the gun can be held in a retracted position automatically, which provides the maximum cooling for the chamber between bursts of fire. This feature is also of extreme importance with large caliber weapons where it is desired to cease firing and to continue the fire immediately without mechanical manipulation. When the bolt has reached the rearward position and the trigger is held pressed, the bolt becomes the driver under the action of the bolt spring, and the frog the driven member.

When the cross-head, which carries the clutch, reaches its rearward position, the clutch disengages when the clutch pawls come in contact with the front face of the frame. This permits the cross-head and the gas piston to move to the rear position ready for the next shot, at the same time eliminating the necessity of returning the clutch to the forward position by the bolt spring, which spring performs this function with a majority of the present automatic guns. The inertia of the frog, when returned by the bolt, causes it to lag behind the bolt which maintains the breech lock in the lowest position, eliminating any friction drag of the breech lock which would be encountered if any tendency to lock were present. The frog in going forward, returns the piston to the forward position through the cross-head, the clutch having been cleared by the clutch pawls.

The present automatic machine gun has been provided with a simple but highly efficient safety. It is of extreme importance when firing larger caliber shells with supersensitive fuses, and of equal importance with any caliber, that the gun be rendered inoperative, should the fired shell be left in the chamber for any reason. It should be impossible to feed a second cartridge against this shell, or portion thereof into the chamber. The same is true should a cartridge be fed into the chamber ahead of the bolt, T-slot, or extractor, and, consequently, fail to fire. The bolt must be retracted to clear such a jam. This retraction normally feeds the next cartridge into alignment with the bore. In the case of a solid shot, the primer of the live round in the chamber will be fired with no support for the base of the cartridge to prevent an explosion with ill consequences, resulting in the destruction of the gun crew and gun should a supersensitive fused cartridge be fed under these conditions. Similarly, a supersensitive fused shell, together with a live round in the chamber, would be fired with the same disastrous results. With the present automatic machine gun, the safety block operates to prevent this accident. The safety block covers a portion of the chamber at all times when the chamber is empty. Consequently, any obstruction in the chamber, such as a shell or cartridge, will force the safety block down, which raises the rear end of the safety lever, thus engaging the bolt on the rearward stroke and arresting the bolt, which prevents the feeding of another cartridge until the chamber has been cleared. Naturally, the safety block does not act when the gun is functioning normally, as the bolt itself clears the obstruction and allows the safety block to raise and lower the safety lever out of the path of the lug of the bolt.

By carrying the breech lock with the bolt, two additional safety features are made possible. One is an extension on the upper portion of the

breech lock that straddles the firing pin head. This extension is provided with a recessed slot, which positively prevents the firing pin from striking the primer until the bolt is completely locked and, in addition, serves to move the firing pin to the rear, clear of the primer recess made by the firing pin, immediately after unlocking begins. In addition, it permits the separation of the sear and sear carrier unit, and causes each to operate separately, yet both depending entirely on the completeness of the locking of the bolt for their release. This design also permits the locking to be accomplished directly in line with the base pressure, as contrasted with the existing types which lock a considerable distance below the actual line of the base pressure and create a turning moment, which disturbs stability.

The counterrecoiling element of the present automatic machine gun takes advantage of new discoveries made in this field and coordinates these discoveries into a simultaneous co-acting couple. The velocity brake at the end of the muzzle is not new as to the killing of the velocity to obtain reduction in recoil. However, what is entirely new in this field is a mechanism so constructed as to present the gases in a uniformly distributed way to the baffling elements so as to obtain the maximum recoil reducing effect, and at the same time to provide a mechanism that will not be obstructed with carbon or residue or other deposits from the firing, and one in which no disturbing force is presented to make the gun unstable, to deflect gases, or direct intense noise and powder gases into the path of the personnel operating the gun.

To provide a stabilizer, in this instance, a central tube is used to overcome the present distortion of the bullet due to the unequal distribution of gases about the base of the bullet, present in all existing recoil muzzle checks, whether they be spiral baffles, direction slots, expansion or contraction chambers with other corresponding escape vents. Some investigators go so far as to claim that these muzzle brakes or recoil checks stabilize the gun by a positive reaction in one or the other direction. The answer to all of this is to so design a successful automatic weapon that the entire action and reaction shall be in one and the same straight line, as a most efficient application of any force is the one applied directly in line with the resistance to be overcome with no deflection in the force arm. The forward pull of the muzzle recoil reducer in the present instance acts in this direction.

With the foregoing and other objects in view, which will appear as the description proceeds, the invention resides in the combination and arrangements of parts and in the details of construction hereinafter described and claimed, it being understood that changes in the precise embodiment of the invention herein disclosed can be made within the scope of what is claimed without departing from the spirit of the invention.

In the accompanying drawings:—

Figure 1 is a side elevation of the complete gun made according to and embodying the present invention, the tripod or mount not being shown, and the water or cooling jacket also being eliminated.

Figure 2 is a top plan view of the rear end of the gun, the barrel being foreshortened.

Figures 3 and 3^a constitute a longitudinal central sectional view through the receiver portion

of the gun and a portion of the barrel, with the parts in the position they assume just after the firing of the cartridge and the setting of the power spring of the gun.

Figures 4 and 4^a are views similar to Figures 3 and 3^a, with the parts in the position they assume at the fully retracted movement of the breech block and during the ejection of a spent cartridge from the receiver, and just prior to the introduction of a new cartridge into the breech.

Figure 5 is a rear elevational view of the breech end of the gun.

Figure 6 is a section taken on line 6—6 of Figure 3.

Figure 7 is a section taken on line 7—7 of Figure 3.

Figure 8 is a section taken on line 8—8 of Figure 3.

Figure 9 is a section taken on line 9—9 of Figure 3.

Figure 10 is a section taken on line 10—10 of Figure 3^a.

Figure 11 is a section taken on line 11—11 of Figure 3^a.

Figure 12 is a longitudinal sectional view taken on line 12—12 of Figure 7, and on line 12'—12' of Figure 8.

Figure 13 is a section taken on line 13—13 of Figure 10.

Figure 14 is a section taken on line 14—14 of Figure 8.

Figure 15 is a view similar to Figure 3 of the receiver end of the gun, showing a modified sear-actuating and operating mechanism.

Figure 16 is an enlarged detail view of the sear-actuating mechanism in the position it assumes after just releasing the sear.

Figure 17 is a section taken on line 17—17 of Figure 15.

Figure 18 is a section taken on line 18—18 of Figure 15.

Figure 19 is a sectional view through the receiver showing the manual releasing sear-actuating mechanism in normal position.

Figure 20 is a similar view showing the mechanism in the position it assumes when retracted and prior to the release thereof.

Figure 21 is a detail longitudinal sectional view through the muzzle dissipater.

Figure 22 is a section on line 22—22 of Figure 21.

Referring to the drawings, in which like reference numerals represent similar parts throughout the several views, and in which, in Figure 15, the primed reference numerals represent similar parts as shown in Figures 3 and 4, the numeral 1 designates the barrel proper of the present gun and 2 the receiver. The gun is supported by means of the trunnions 3 and the yoke 4 on a tripod T and is supported at its rear by the lug 5 and the adjusting screw 6 operated by the elevation control wheel 7. The present type of gun is also constructed to be mounted upon any form of mount, as it can be used as a tank or anti-tank gun, as well as an aircraft or anti-aircraft gun.

A magazine 8 is adapted to feed the cartridges C' into the receiver, and although here shown as a casing, the same is indicative of a belt feed mechanism. The barrel 9 is fitted into the supporting portion 6^a of the receiver, as at 10, being provided with the breech 11 for the reception of the cartridge C, the cartridges being fed into the receiver through the opening 12.

A breech block 13, which is capable of straight

line reciprocating movement within the receiver and is mounted for sliding movement between the strips 14, is also provided with the oppositely disposed end guiding lugs 16. Mounted within and 5 carried bodily by the breech block is the firing pin 17 which is normally propelled forward by the spring 18 so that the fulminate cap-engaging end 19 may be projected through the opening 20 of the breech block to engage the fulminating cap 10 of the held cartridge C. The rear end of the firing pin is adapted to be projected beyond the rear space of the breech block so that its head 21 will be in the path of and be automatically engaged by the shoulder 36 of the automatic sear 15 33 which is mounted for vertical sliding movement within the recess 32 of the receiver and is held downwardly in place by means of the spring 34 and the cap 35.

Also associated with and carried by the breech 20 block are the cartridge extractors 22, the forward ends 23 of which are disposed forwardly of the breech block for engaging the rim of the cartridge C while the same is within the breech and to be automatically actuated to withdraw the same 25 upon the rearward movement of the breech block, so that when the empty case is alined with the members 24, as viewed in Figures 8 and 14 the portions 24^a thereof will be projected outwardly and above the case to cause the same to be 30 ejected from the receiver. These members 24 are mounted in the oppositely disposed casings 25 and are normally held outwardly in the path of the breech block by means of the springs 26, the forward movement of said breech block retracting 35 said members within the casings, while the rearward movement permits the springs 26 to act as above set forth.

The breech-block is provided with the lug 27, the purpose of which will presently appear, and 40 with the open depending member 28 which constitutes a guide for the lock 29 and is of vast importance. The lock 29 is provided with the abutting portion 30 disposed to be placed, at the proper time, between the rear end of the breech block 45 and the portions 30^a of the receiver so as to momentarily lock the breech block against rearward movement and during the engagement of the sear-releasing device 31 carried thereby, which, as shown, is adapted to enter the opening 50 32 and elevate the automatic sear 33 so that the portion 36 thereof is moved out of engagement with the head 21 and, consequently, release the firing pin simultaneously with the final locking position of the bolt. Thus, it will be seen that 55 the lock 29 is carried bodily by the bolt or breech block in its reciprocating movement and is only brought into locking engagement shortly after the retraction of the firing pin by engagement with the automatic sear 33 and the release 60 thereof for exploding the fulminating cap.

To assist in the forward movement of the breech block, a casing 36, open at one end, is held within the member 28 by means of the lock nut 37, and bodily disposed within this member is a 65 tube 40 provided at its free end with the plunger or piston 41 fitting within the cylinder 42 fixed at 43 to the rear end 44 of the receiver.

Mounted within the telescopic members 40 and 70 42 is the auxiliary spring 45 which acts to move the breech block into breech-closing and locking position, the same being abutted by the shoulder b carried by the guide pin 47 and housed within the casing 46 detachably connected at the rear end of the receiver and upon the end 43 of the sleeve 42.

Mounted within the casing 46 is a plunger 48 which is held forwardly by means of the spring 50, while mounted for adjusting the rod 47 is a milled finger wheel or button 48, the purpose of which will presently appear.

Connected to the barrel 9 forwardly of the receiver is a band 51 which, as shown, has secured therein the rear end of the cylinder 52, and has a port 53 leading from the bore of the barrel 9 into the rear end of said cylinder so that the gases 10 issuing therefrom act upon the piston 54 to move the piston forwardly, the purpose of which will presently appear. This piston 54 is connected to the forward end of the rod 55 which is threadedly engaged at 56 to the cross head 57 slidably mounted and guided by the barrel 9 and the guide rod 59, said guide rod 59 being mounted throughout the opening 58 of the cross head 57 and attached, as at 60, to the member 51. The rear end of the rod 59 is mounted in the solid portion 20 61 of the receiver and the entire mechanism at this point is surrounded by a casing 62.

As shown in Figures 3^a and 10, the forward end of the rod 67 is connected to the cross head 57 in an unusual manner, there being disposed in 25 the bore 63 the inwardly moved blocks 65 whose springs 65^a engaging the blocks 64 hold the inner ends thereof in the path of the rod 67 to be engaged thereby, the purpose of which will presently appear. The ends 66 of the lock 65 are disposed, 30 as shown in Figure 13, to abut the end of the rod 67, and attached to this rod are the two pins 68 which slide within the openings 69 of the bifurcated members 70.

Attached to the rear end of the rod 67 and 35 adapted to be movable with the same at all times is a link R carrying a setting pin 72 and a bifurcated end 73, each member of which is provided with the angular rectangular recess 74, and a sear 75. A pin 77 is mounted in the locking block 29 40 and is engaged at its ends by means of the rectangular blocks 76, said blocks 76 being mounted within the openings 74 so that when the link R is reciprocated, vertical reciprocating movement 45 is imparted to the locking member 29.

In order to pull the link R and also the breech block 13 rearwardly against the action of the spring 45 to initially set the present mechanism before the first cartridge is fired, the rod 78 is pulled manually rearwardly through means of the eye 79 so that the hook terminal 80 will engage the pin 72, the same being pulled until the catch 15 engages the trigger 81, at which time, the breech block and mechanism is locked in full rearward position and the spring 45 is placed under tension. The trigger 81 is mounted within the casing 82 formed at the rear under side of the receiver and is itself provided with a recess 83 for the reception of the rounded end 84 of the trigger or hand-operated member 85 mounted on the pin 86 at the upper portion of the hand guard 87 and in ready access to the operator of the present gun.

Connected to the forward end of the rod 55 is 65 a rod 89 which is mounted to move within the forward extension 90 of the cylinder 52 and against the action of the spring 91 to abut, at the final stroke of the piston, the buffer 92 (Fig. 21) held in place by means of the cap 93 at the extreme 70 end of the extension 90. By this means, the spring 91 is compressed due to the forward propulsion of the piston 54 and the shock upon the member 89 is taken care of by the buffer 92 at the extreme engagement of the piston 54 and just 75

after the escape of the gas through the openings 88 (Fig. 3a).

Mounted within the receiver to be engaged by the projection 27 of the breech block is a pivoted lever 94 mounted upon the pin 95 within the receiver and provided with the rear weighted portion 96 so that the member normally assumes the position as shown in Figure 4 for movement to the position as shown in Figure 3 by the engagement of the lug 27 therewith so that the forward rounded end 97 mounted within the bore 98 of the plug 99 will move the block 100 to the lowermost position and against the action of the springs 105 which hold the pin through its head 103 upwardly within the bores 104, so that the safety block 100 will move to assume the position as shown in Figure 4. Thus, should a shell remain within the breech of the barrel, the introduction of a new cartridge therewithin will be prevented and the mechanism will be locked against further movement. In the construction illustrated in Figures 15, 16, 17, and 18, a modified arrangement of sear is shown mounted at the top of the receiver covered by the lid 106. This comprises a double lever 107 mounted in place by means of the pin 108 between the ears 109 thereof, and mounted in the forward end thereof, in the recess 110, and held against upward displacement by means of the plate 111, is a catch or bolt 113 propelled downwardly by means of the spring 112 for engagement with the edge 114 of the sear 21' of the firing pin. Also, to assist in moving the lever 107 from locked position, as shown in Figure 15, to released position, as shown in Figure 16, in the free end of the lever 107 two pins 116 are carried, which pins are spring-propelled by means of the spring 117 so that their lower ends will engage the upper portion of the lugs 115 carried by the locking bolt 30'. Thus, it will be seen that when the locking bolt is elevated into breech-locking position, the members 115 will engage the pins 116 and thus automatically elevate the free end of the lever 107 so as to release the firing pin. In order to provide a means whereby this release may be performed manually, the rear end 119 of the lever 117 is adapted to be engaged by the portion 120 of the sliding bolt 118 mounted above the receiver and within the rear end of the lid 106. This is accomplished through the instrumentality of the slot 121 and the head 122 of the bell-crank lever 123, which lever is mounted upon the pin 124 between the projections 125 of the receiver and is manually operated through the pin 126, link 127, pin 128, and the trigger block 81', the detail construction of which has been heretofore set forth.

The present type of gun is so constructed that in the event of a misfire the firing pin can be manually set and released and thus freed an indefinite number of times before opening the breech to remove the misfired cartridge, the particular mechanism for accomplishing this being clearly shown in Figures 19 and 20 in which a lever 129 with a hand-piece 130 is mounted for pivotal and sliding movement through the instrumentality of the slot 131 and pin 132 at the right-hand rear side of the receiver, its forward hooked end 134 being disposed to be projected through the opening 135 against the spring 136 so as to engage the hook 137 attached to the block 21' of the firing pin 17'. By this means, the firing pin may be moved from the position shown in Figure 19 to that shown in Figure 20 to be released by pushing the end 130 toward the receiver and out of engagement with the hook

137. This operation may be repeated any number of times.

In the construction of muzzle dissipater shown in Figures 1, 21 and 22, the outer casing 130 is provided with a central tube 131 which acts as a guide for the bullet with perforations 132 therethrough, said tube providing a chamber 134 at the inlet end outletting at the periphery 135 between the outer edge of the spiral 136 and the inner face of the casing 130. Thus, the gases 10 emitting from the muzzle are directed into the chamber at the inner end thereof, and are diffused through the spiral chamber, the perforations of the tube and the tube so as to act as a brake at the muzzle of the gun. 15

By having the spiral disconnected at the periphery with the inner walls of the chamber, collection of carbon or dirt is prevented, and the same is finally carried out through the outlet 20 of the dissipater.

As shown in Figure 15 of the drawings, the member 115, as the bolt 30' is elevated into locking position at the rear of the breech block 13' and after the final locking of the same, engages the free end of the lever 107', and thus 25 releases the sear so that the firing pin is released to explode the fulminating cap. This particular construction dispenses with the link 127 and the parts operated thereby. 30

I claim:—

1. A machine-gun including a receiver, a barrel connected thereto, a breech block reciprocatingly mounted within the receiver for straight line movement to and from the breech of the barrel, a spring propelled firing pin bodily carried by the breech block, a fixed locking member mounted in the receiver, a vertically movable lock bodily carried by the breech block for cooperation with the fixed member when the breech block is in breech-closing position, means for retracting the firing pin during the closing of the breech, the same being released to free the firing pin by the movable lock as the latter completes its final locking movement, and a device connected to the breech block for causing limited sliding movement of the movable lock, whereby the lock is released before the breech block is started on its rearward movement. 35

2. A machine-gun including a receiver, a barrel connected thereto, a breech block reciprocatingly mounted within the receiver for straight line movement to and from the breech of the barrel, a spring propelled firing pin bodily carried by the breech block, a fixed locking member mounted in the receiver, a vertically movable lock bodily carried by the breech block for cooperation with the fixed member when the breech block is in breech-closing position, and a device connected to the breech block for causing limited sliding movement of the movable lock, whereby 50 the lock is released before the breech block is started on its rearward movement, gas-set and spring-actuated means mounted in the receiver and connected to said breech block for imparting rearward movement to the breech block, 55 means mounted in the receiver and in the path to engage and set the firing pin as the breech block is moved into closing position, said means being released by the movable lock when said lock is moved into final locking position, and a 60 spring compressed during said rearward movement to impart forward and closing movement to the breech block after releasing of the first 65 spring. 70

3. A machine-gun, including a receiver, a bar- 75

- rel connected thereto, a breech block reciprocatingly mounted within the receiver for straight-line movement to and from the breech of the barrel, a fixed locking member mounted in the receiver, a movable lock bodily carried by the breech block for cooperation with the fixed locking member when the breech block is in breech-closing position, gas-set and spring-actuated means connected to said breech block for imparting rearward movement to the breech block, a spring compressed during rearward movement to impart forward and closing movement to the breech block after release of the first spring, a spring-propelled firing pin carried bodily by the breech block, means for coincidentally setting the firing pin at the close of the breech by the breech block, and means carried by the movable member of the lock for releasing the same at the final locking of the breech block.
20. 4. A machine-gun, including a receiver, a barrel connected thereto, a breech block reciprocatingly mounted within the receiver for straight-line movement to and from the breech of the barrel, a fixed locking member mounted in the receiver, a movable lock bodily carried by the breech block for cooperation with the fixed locking member when the breech block is in breech-closing position, gas-set and spring-actuated means connected to said breech block for imparting rearward movement to the breech block, a spring compressed during rearward movement to impart forward and closing movement to the breech block after release of the first spring, manually operated means is provided for moving the breech block against the action of the second spring to set the same.
5. A machine-gun, including a receiver, a barrel connected thereto, a breech block reciprocatingly mounted within the receiver for straight-line movement to and from the breech of the barrel, a fixed locking member mounted in the receiver, a movable lock bodily carried by the breech block for cooperation with the fixed locking member when the breech block is in breech-closing position, gas-set and spring-actuated means connected to said breech block for imparting rearward movement to the breech block, a spring compressed during rearward movement to impart forward and closing movement to the breech block after release of the first spring, in which means is provided to prevent the closing of the breech block in case of a misfire and a spent cartridge shell remains in the breech of the barrel.
55. 6. A machine-gun including a receiver, a barrel connected thereto, a breech block reciprocatingly mounted within the receiver for straight-line movement to and from the breech of the barrel, a fixed locking member mounted in the receiver, a movable lock bodily carried by the breech block for cooperation with the fixed member when the breech block is in breech-closing position, gas-set and spring-actuated means connected to said breech block for imparting rearward movement to the breech block, a spring compressed during said rearward movement to impart forward and closing movement to the breech block after release of the first spring, a spring-propelled firing pin carried bodily by the breech block, means for coincidentally setting the firing pin prior to the closing of the breech, means carried by the movable member of the lock for releasing the firing pin at the final locking of the breech block, and manually controlled means for setting and releasing the firing pin
- after the same has been automatically released and the breech block is still in locked position.
7. A machine-gun according to claim 6 in which there is provided a means for locking the breech block against closing action due to the retention in the breech of a deformed cartridge casing.
8. A machine-gun including a receiver, a barrel attached thereto, a gas-actuated and spring-returned plunger mounted adjacent to the barrel, a rod connected to the plunger and extending into the receiver, a breech block mounted in the receiver for straight line movement to and from the breech of the barrel, a locking member carried by the receiver, a slideable locking member carried by the breech block, and cooperating means carried by the slideable locking member and plunger-actuated rod for imparting vertical reciprocating movement to the locking member during the locking and unlocking of the breech block.
9. A machine-gun according to claim 8 in which there is a spring opposing the rearward movement of the breech block and for propelling the breech block into breech-closing position and for moving the locking member carried thereby into locking position, a firing pin carried by the breech block, means disposed in the path of the firing pin for setting the same during the closing of the breech block, and means carried by the movable locking member for releasing the firing pin when the breech block is fully locked.
10. An automatic gun according to claim 1, in which there is a tube disposed parallel with the barrel and in communication with the bore of the barrel at a point where the ordinate of the powder curve is at its maximum, and a spring returned plunger mounted in the tube and operated in a forward direction by the gases of explosion admitted to the tube to produce a counter-recoil action to the gun.
11. An automatic gun according to claim 6, in which there is a tube disposed parallel with the barrel and in communication with the bore of the barrel at a point where the ordinate of the powder curve is at its maximum, and a spring returned plunger mounted in the tube and operated in a forward direction by the gases of explosion admitted to the tube to produce a counter-recoil action to the gun.
12. An automatic gun according to claim 8, in which there is a tube disposed parallel with the barrel and in communication with the bore of the barrel at a point where the ordinate of the powder curve is at its maximum, and a spring returned plunger mounted in the tube and operated in a forward direction by the gases of explosion admitted to the tube to produce a counter-recoil action to the gun.
13. An automatic gun according to claim 1, in which there is a tube disposed parallel with the barrel and in communication with the bore of the barrel at a point where the ordinate of the powder curve is at its maximum, a spring returned plunger mounted in the tube and operated in a forward direction by the gases of explosion admitted to the tube, and a braking device at the muzzle of the barrel and upon which the gases of explosion act in cooperation with the plunger to produce a counterrecoil action to the gun.
14. An automatic gun according to claim 6, in which there is a tube disposed parallel with the barrel and in communication with the bore of the barrel at a point where the ordinate of the powder curve is at its maximum, a spring re-

turned plunger mounted in the tube and operated in a forward direction by the gases of explosion admitted to the tube, and a braking device at the muzzle of the barrel and upon which the gases of explosion act in cooperation with the plunger to produce a counterrecoil action to the gun.

15. An automatic gun according to claim 8, in which there is a tube disposed parallel with the barrel and in communication with the bore of the barrel at a point where the ordinate of the power curve is at its maximum, a spring returned plunger mounted in the tube and operated in a forward direction by the gases of explosion admitted to the tube, and a braking device at the muzzle of the barrel and upon which the gases of explosion act in cooperation with the plunger to produce a counterrecoil action to the gun.

16. A machine-gun including a receiver, a barrel connected thereto, a breech block reciprocatingly mounted in the receiver for straight line movement, a fixed locking member mounted in the receiver, a movable lock bodily carried by the breech block for cooperation with said fixed member when the breech block is in breech-closing position, gas-set and spring actuated means connected to said breech block for imparting rearward movement to the breech block, a spring compressed during said rearward movement to impart forward and closing movement to the breech block at the release of the first spring, a spring propelled firing pin carried bodily by the breech block, means for coincidently setting the firing pin at the closing of the breech, and means carried by the movable member of the lock for releasing the same at the final locking of the breech block.

17. A machine gun according to claim 16, in which there is provided a means for locking the breech block against closing action due to the retention in the breech of a deformed cartridge casing or a misfire.

18. A machine gun according to claim 16, in which there is a tube disposed parallel with the barrel and in communication with the bore of the barrel at a point where the ordinate of the powder curve is at its maximum, and a spring returned plunger mounted in the tube and operated in a forward direction by the gases of explosion admitted to the tube to produce a counterrecoil action to the gun.

19. An automatic gun, including a receiver, a barrel attached thereto, a breech block mounted in the receiver for movement to and from the breech of the barrel, a spring propelled firing pin carried by the breech block, a gas-set and spring returned plunger mounted adjacent to the barrel, means for determining the amount of power stored in the spring independent of variation of powder pressure, a rod mounted for reciprocation within the receiver, and cooperative means carried by the rod and the breech block whereby the breech block and rod are permitted independent forward movements and whereby the rod will move the breech block rearwardly when the plunger and rod are spring propelled, and means for setting the firing pin mounted in the receiver, the latter being released at the final closing of the breech block.

20. An automatic gun according to claim 19, in which a tube is disposed parallel to the barrel and has a port in communication with the barrel, the plunger being mounted in the tube, said port being at a point where the ordinate of the powder curve is at its maximum.

21. An automatic gun, including in combination a receiver, a barrel attached thereto, a breech block mounted in the receiver for straight line movement, a spring propelled firing pin carried by the breech block, means for reciprocating the breech block, means carried by the receiver in the path of the firing pin for setting the same as the breech block is moved into breech closing position, and means carried by the breech block for engaging the setting means to release the firing pin.

22. An automatic gun as claimed in claim 21, in which manually operated means is provided for retracting and releasing the firing-pin independent of movement of the breech-mechanism.

23. An automatic gun as claimed in claim 21, in which means is provided for preventing the closing of the breech block and the introduction of a new cartridge in the breech of the barrel should a portion of a spent shell or a spent shell remain in the breech of the barrel.

24. In a gun, a receiver, a bolt, and locking and shifting means for the bolt in the receiver including a locking member, means for moving the locking member to operating and inoperating positions, said means having an inclined slotted connection with the locking member permitting the lock to have a movement independently of the bolt, but at a predetermined position upon shifting the bolt in one direction, and other means for forcing the bolt in the reverse direction whereby the slotted connection is maintained under pressure to hold the lock in retracted position to prevent movement thereof in a locking direction.

25. In a gun, a receiver, a bolt, and locking and shifting means for the bolt in the receiver including a locking member, means for moving the locking member to operating and inoperating positions, said means having an inclined connection with the locking member permitting the lock to have a movement independently of the bolt, but at a predetermined position upon shifting the bolt in one direction, and other means for forcing the bolt in the reverse direction whereby the connection is maintained under pressure to hold the lock in retracted position to prevent movement thereof in a locking direction.

26. In a gun, a receiver, a bolt, and locking and shifting means for the bolt in the receiver including a locking member, means for moving the locking member to operating and inoperating positions, said means having an inclined loose connection with the locking member permitting the lock to have a movement independently of the bolt, but at a predetermined position upon shifting the bolt in one direction, and other means for forcing the bolt in the reverse direction whereby the loose connection is maintained under pressure to hold the lock in retracted position to prevent movement thereof in a locking direction, the arrangement of the parts permitting the lock actuating means to operate under momentum when the bolt has been positioned in its return movement to move the lock into locking position relative to the bolt.

27. In a gun, a bolt having a straight line movement, means for actuating the same, and means for locking the bolt against movement comprising a locking member movable in a rectilinear path to have a substantial bearing at right angles to its longitudinal axis and substantially in line with the center of load to be applied thereto.

28. In a gun, a bolt having a straight line

- movement, means for actuating the same, and means for locking the bolt against movement comprising a locking member movable in a rectilinear path to have a substantial bearing at right angles to its longitudinal axis and substantially in line with the center of load to be applied thereto, the rear face of the lock being wedge-like to crowd the bolt home when the lock is forced into locking position.

5 29. An automatic gun including a receiver, a breech block mounted for movement in the receiver, a movable locking member for locking the breech block in closed position, a spring-propelled firing-pin carried by the breech block, means for setting the firing-pin at the closing of the breech block, said lock releasing the firing pin upon locking of the breech block, and means for manually controlling the releasing of the firing-pin independent of the locking of the breech block.

10 30. An automatic gun including a receiver, a breech mechanism mounted for reciprocating movement in the receiver, means for moving the breech mechanism to the rear, other means for moving the breech mechanism forwardly, a spring-urged firing-pin carried by the breech mechanism, means for setting and releasing the firing-pin upon closing of the breech mechanism, means for manually controlling the releasing of the firing-pin, and a manually controlled sear for engaging the breech mechanism when in its rearward position to hold the breech mechanism open.

15 31. An automatic gun including a receiver, a breech mechanism mounted for movement in the receiver, a spring-urged firing-pin carried by the breech mechanism, means for setting and releasing the firing-pin upon closing of the breech mechanism, means for reciprocating the breech mechanism to cause automatic operation of the gun upon the firing of a cartridge, means for manually controlling the releasing of the firing-pin, and a manually controlled member for catch-

20 ing and holding the breech mechanism when in its rearward position.

25 32. An automatic gun including a receiver, a barrel attached to said receiver and having a gas port adjacent the breech end thereof, a breech mechanism movably carried in said receiver, piston means actuated in a forward direction by gases from said port, and power storage and counter-recoil abutting instrumentalities including the gas actuated piston means, a spring adapted to be compressed under the actuation of said piston means for storing power to operate said breech mechanism, a counter-recoil abutment fixed forwardly to the gun, means for effecting a positive abutting relationship between the piston means and the abutment at the final stroke of the piston means, said abutment being substantially non-resilient and non-recovering so as to transmit to the associated parts of the gun the forward force of the piston means which is in a direction opposite to the recoil force of the gun.

30 33. In an automatic gun having a barrel, shell ejecting and re-loading mechanism, piston means associated with said mechanism to actuate the same, a cylinder attached to said barrel and in communication therewith to receive gas therefrom, resulting from the explosion of a power charge, an abutment secured to said cylinder and energy storing means in said cylinder means, said piston and cylinder means and energy storing means being so related in said gun that said powder gases actuate said piston means forwardly of the gun and transmit energy to said energy storing means, said energy storing means thereafter furnishing the energy to actuate the piston means and said mechanism; the combination of a substantially non-resilient abutment means between said aforementioned abutment and said piston means to limit the amount of energy stored in said energy storing means and whereby the excess energy will be substantially all transmitted to said gun in a forward direction.

35 40
